UNITED STATES PATENT OFFICE.

FRANK H. CARSON, OF LANSING, ILLINOIS.

HOT-AIR FURNACE.

Application filed July 30, 1925. Serial No. 47,114.

This invention relates to certain new and useful improvements in hot air furnaces, and has more particular reference to a furnace of this kind embodying a vertical fuel magazine.

The primary object of the invention is to generally simplify and improve hot air furnaces of the above kind whereby the same will be extremely simple and durable 10 in construction as well as efficient in operation.

Another object is to so construct a hot air furnace as to embody means for permitting and insuring complete combustion of the fuel 15 under various conditions of use and in such manner as to obtain the greatest possible heating efficiency.

Other objects will appear as the nature of the invention is better understood, and the 20 same consists in the novel form, combination and arrangement of parts hereinafter more fully described, shown in the accompanying drawings and claimed.

In the drawings, wherein like reference 25 characters indicate corresponding parts throughout the several views,

Figure 1 is a front elevational view, partly broken away and in section, of a hot air furnace constructed in accordance with the present invention,

Figure 2 is an enlarged fragmentary horizontal section taken substantially upon line 2-2 of Figure 1,

Figure 3 is a developed perspective view 35 illustrating one of the devices for securing the removable casing section of the furnace in place,

Figure 4 is a substantially central vertical sectional view of the furnace shown in Figure 1,

Figure 5 is a vertical sectional view taken substantially upon line 5-5 of Figure 4,

Figure 6 is a horizontal section taken substantially upon line 6-6 of Figure 4,

Figure 7 is a horizontal section taken substantially upon line 7-7 of Figure 4,

Figure 8 is a view similar to Figure 7, taken upon line 8-8 of Figure 4,

Figure 9 is a view similar to Figure 8 taken on a horizontal plane somewhat below the section line 8-8, and

Figure 10 is a vertical section taken substantially upon line 10-10 of Figure 9.

Referring more in detail to the drawings, the form of the invention herein illustrated

consists of a flat or horizontal hollow base 5 forming an ash pit and provided with a door 6 for facilitating removal of the ashes therefrom. The base 5 has a central opening in its top wall and is formed with an up- 60 standing fire pot 7 in surrounding relation to this opening, the fire pot being also equipped with a front door 8 to permit poking of the fuel should the same be found necessary. 65

As shown more clearly in Figures 9 and 10, a grate structure is supported by the top wall of the base 5 and is arranged within the central opening in the latter. This grate structure embodies a ring 9 provided at its top edge with horizontal outwardly projecting radial lugs 10 which seat in suitable radial grooves or sockets formed in the top wall of the base 5 and indicated at 11 in Figure 10. The ring 9 is thus restrained from rotation relative to the base 5 although capable of being removed from the latter, and projecting inwardly from the lower edge of the ring 9 is a horizontal annular flange 12, the upper surface of which is formed with radial teeth as shown clearly in Figure 9 so as to constitute a horizontal gear. The grate proper embodies a pair of concentric rings 13 and 14 between which are disposed a circular series of radially extending grate bars 15 that are secured upon shafts 16 whose end portions are journaled in the rings 13 and 14. The shafts 16 project outwardly through the outer ring 13 where they are provided with pinions 17 that mesh with the gear 12, and it will thus be seen that when the grate proper is given a rotary reciprocating movement, the grate bars will be given a shaking movement as well as an axial turning or dumping movement. In other words, the grate bars 15 will be reciprocated in an arcuate path and by reason of the fact that the pinions 17 mesh with the stationary gear 12, said grate bars will also be given a rotary reciprocating movement bodily about their radial axes or with their shafts 16 on which the pinions 17 are fastened. This provides a very efficient grate structure by means of which all completely consumed fuel may be caused to pass into the ash pit. 100

An outer drum 18 is pivotally arranged above the fire pot 7 and has its lower edge portion seated within a groove or flange on the upper edge of said fire pot as shown 110

clearly in Figure 4, and disposed within and in spaced concentric relation to the outer drum 18 is a second or inner drum 19 within and in spaced concentric relation to which 5 is disposed a central vertical fuel magazine 20 preferably of the tapered form shown. The lower edges of the drum 19 and magazine 20 are disposed slightly above the upper edge of the fire pot 7 and are rigid with 10 an annular horizontal tube 21 which closes the space between the lower ends of the drum 19 and magazine 20 and has a series of openings therethrough on its under side as indicated at 22. The space between the 15 inner drum 19 and magazine 20 is open at the top of said drum 19 with the exception of points where these parts are rigidly connected by radial webs 23 as shown in Figures 4 and 7, and formed on the upper edge 20 of the inner drum 19 is an outwardly projecting annular flange of angular cross section as indicated at 24, the depending free edge portion of the flange 24 being seated in a groove of annular form provided in the 25 edge portion of an inwardly and upwardly tapering flange 25 provided on the upper edge of the outer drum 18. The flange 25 may be fixed to the drum 18 after the drum 19 and magazine 20 are positioned in place, 30 and it will thus be seen that the structure embodying the rigidly connected drum 19 and magazine 20 is effectively supported so that the parts are disposed as shown in Figure 4 with the tube 22 disposed above 35 the fire pot 7 and adjacent the side wall of the latter. It is also obvious that a packing may be provided at the joint between the flanges 24 and 25 so that the space between the drums 18 and 19 is effectively 40 closed at the top of the latter.

The fire spot 7 is provided with an external annular hollow band 26 which is horizontally disposed between the top and bottom edges of the fire pot and which is 45 provided with an inlet opening 27, the fire pot 7 being formed with a horizontal series of openings 28 which communicate with the interior of the band 26 so that air may pass from within said band into the fire pot 50 entirely around the latter. A tube 29 extends from the outside of the outer drum 18 to and communicates with the tube 21 so that air may be supplied to the latter for 55 ultimately passing outwardly and downwardly through the outlet openings 22 toward the fire pot and the openings 28 of the latter. The admission of air to the tube 29 and band 26 may be controlled by a suitable damper 30 associated with the inlet opening 27 and the outer end of the tube 29, the arrangement being such as to permit simultaneous passage of air to these parts, 60 or not, as desired.

The magazine 20 projects a considerable 65 distance above the tops of the drums 18 and

19, and communicating at their upper ends with the interior of this upper projecting portion of the magazine 20 are vertical tubes or pipes 31 whose lower ends communicate with opposite sides of the base or ash pit 5. 70 A plurality of spaced horizontal tubes 32 connect the drums 18 and 19 and provide means for supplying air from the exterior of the outer drum 18 to the interior of the inner drum 19 or the space between said 75 drum 19 and the magazine 20. It will thus be seen that the air will pass into the lower part of the space or chamber within the drum 19 and around the magazine 20 and then will pass upwardly to be heated, such 80 heated air ultimately passing out of the upper end of the inner drum 19 and into the space provided within the top of a casing 33 which surrounds the drum 18, fire pot 7 and ash pit 5 and is in spaced relation to said drum 18 as shown clearly in Figure 4. The top of the casing 33 is provided with a plurality of hot air outlet pipes 34 by means of which the heated air may be 85 conducted to the various rooms of a dwelling or the like. Arranged within the casing 33 in surrounding relation to the magazine 20 and above the upper end of the outer drum 18 is a horizontal annular tube 35 which has depending nipples 36 telescoped onto upstanding nipples provided on the flange 25, whereby products of combustion may pass from the space between the drums 18 and 19 into the pipe 35. The pipe 35 is further connected to a smoke pipe 37 and the latter extends rearwardly through the casing 33 and may be connected in any well known or preferred manner with the chimney of the building in which the furnace is employed. A suitable handle 38 90 may be attached at its inner end to the grate ring 14 for facilitating shaking of the grate, the outer end of the handle 38 being projected through a horizontal elongated slot as at 39 provided in the casing 33 as shown 95 best in Figure 1. The magazine 20 is preferably provided with a removable cover 40 for facilitating introduction of the fuel, and the upper end portion of the magazine 20 projects upwardly through a central opening in the top wall of the casing 33 for 100 facilitating access to the cover 40.

A pipe or tube 41 has its ends secured in 105 openings in the drum 18 and magazine 20 and extends through an opening in the drum 19, and this pipe 41 provides means for permitting entrance of air from the outside of the outer drum 18 to the interior of the magazine 20 directly above a fire built in the furnace. A damper 42 is provided 110 at the outer end of the pipe 41 so as to control the amount of air admitted.

The casing 33 is preferably constructed 115 of inner and outer sheet metal walls 33 and 34 arranged in spaced relation, the space be- 120

tween the walls being filled by asbestos sheets 45.

The casing 33 preferably embodies a removable section of any desired size and generally indicated by the reference character S. This removable section is preferably tapered along its vertical edges to provide V-shaped tongues, and the adjacent vertical edges of the body of the casing 33 10 are formed to provide V-shaped grooves in which these tongues are adapted to be snugly fitted as generally indicated at 46. The removable section S of the furnace casing 33 is held in place by suitable securing devices, each of which is of the form clearly shown in Figures 1 to 3 inclusive. As shown, each securing device embodies a bifurcated member 47 preferably formed 15 from a return-bent strip of metal so as to provide the legs of the bifurcation with superimposed eyes as at 48. Each fastener also includes a member 49 adapted to be disposed between the bifurcations of the member 47 and formed with an eye as at 50 20 adapted to align with the eyes 48 for removable reception of a wedge 51 whereby the members 47 and 49 may be separably connected with the adjacent edge portions of the furnace body and its removable section drawn tightly together. The member 49 preferably consists of a strip of metal return bent so as to have the eye 50 formed at its intermediate portion. It will thus be seen that when the members 47 are secured 25 to the body of the casing 33 and the members 49 secured to the removable section S, the latter may be firmly held in place with the meeting edges of the casing body and its removable section in air tight relation. By removing the wedges 51 the section S may be readily removed for permitting access to the parts within the casing when their renewal or repair is found necessary. The casing 33 is provided with 30 a relatively large door 52 which may be opened for permitting access to the doors 6 and 8, and extending through a side of the casing 33 is a cold air pipe 53 whose inner end communicates with the interior of the casing 33 at one side of the latter and as best shown in Figures 1, 4 and 6. The pipe 53 supplies cold air to the furnace and particularly to the space between the casing 33 and the outer drum 18 at the bottom of 35 said space so that air will be supplied for passing into the space between the inner drum 19 and the magazine 20 through the pipes 32.

The pipe 53 is provided with a side opening closed by means of a door 54, and arranged within the pipe 53 adjacent the door is an air moistening and cleaning device consisting of a water pan 55 adapted to be placed into the pipe through the door opening of the door 54 so as to rest upon

the bottom wall of said pipe 53 as shown in Figure 4. A screen 56 extends across the interior of the pipe 53 so that all air passing through the pipe 53 will have to pass through this screen for being cleaned, and supported by the screen 56 are a plurality of which 57 whose lower ends project into the water within the pan 55 so as to be kept saturated for moistening the air coming in contact therewith in its passage from the pipe 53 to the furnace.

In operation the fire is built upon the grate within the fire pot, and air is admitted through the openings 27 and 28 from the annular tube 22 and the belt 26 when the damper 30 is opened for admitting air to the tube 22 and belt 26. The air passes outwardly through the openings 27 and 28 in opposed jets, thus effectively promoting combustion of the fuel evenly on all sides or entirely about the fire pot. The unconsumed gases will pass into the upper ends of the pipes or tubes 31 and then downwardly through the latter into the ash pit 5 for being ultimately allowed to rise 90 through the fuel and there consumed. Further and more complete combustion may be had by admitting air through the pipe or tube 41 by opening the damper 42, the latter air mixing with the unconsumed gases 95 referred to above. The products of combustion will also be drawn from all sides of the fire pot upwardly into the space between the drums 18 and 19, to ultimately pass into the horizontal circular or annular 100 tube 35 and then through the smoke pipe 37 so as to pass from the latter to the chimney. By allowing part of the products of combustion to be drawn into the tube 35 from all sides of the fire pot by the 105 chimney draft, even combustion of the fuel in the fire pot is insured. The air entering the tubes 32 and passing therefrom upwardly in the space between the inner drum 19 and magazine 20 will be effectively heated 110 and will rise in a heated column into the space above the drums within the top of the casing 33, from whence it will be led to the desired points or rooms through the pipes 34. Any suitable means may be provided 115 for permitting control of the dampers 42 and 30 from the exterior of the casing 33.

From the foregoing description it is believed that the construction and operation 120 as well as the advantages of the present invention will be readily understood and appreciated by those skilled in the art.

Minor changes may be made without departing from the spirit and scope of the invention as claimed.

What I claim as new is:

1. In a hot air furnace, a fire pot, an outer drum on the fire pot, an inner drum within and spaced from the outer drum, a vertical 130

magazine within and spaced from the inner drum and projecting above the latter, an annular horizontal perforated tube closing the space between the lower ends of the inner drum and the magazine, means to conduct air from the exterior of the outer drum to said perforated tube, an annular hollow band on the outside of the fire pot, said fire pot having a series of openings communicating with said band, means to control the flow of air to said perforated tube and said band, a casing surrounding the drums and forming a space above the latter to which heated air may pass from the space between the inner drum and the magazine, pipes for conducting the heated air from the space above the drums, and means to conduct air from the exterior of the outer drum to the lower part of the space between the inner drum and the magazine.

2. In a hot air furnace, a fire pot, an outer drum on the fire pot, an inner drum within and spaced from the outer drum, a vertical magazine within and spaced from the inner drum and projecting above the latter, an annular horizontal perforated tube closing the space between the lower ends of the inner drum and the magazine, means to conduct air from the exterior of the outer drum to said perforated tube, an annular hollow band on the outside of the fire pot, said fire pot having a series of openings communicating with said band, means to control the flow of air to said perforated tube and said band, a casing surrounding the drums and forming a space above the latter to which heated air may pass from the space between the inner drum and the magazine, pipes for conducting the heated air from the space above the drums, and means to conduct air from the exterior of the outer drum to the lower part of the space between the inner drum and the magazine, the space between said drums being in communication with the interior of the fire pot, a smoke pipe communicating with the interior of the magazine, and an annular tube above the drums and communicating with the smoke pipe and the top of the space between the drums.

3. In a hot air furnace, a fire pot, an outer drum on the fire pot, an inner drum within and spaced from the outer drum, a vertical

magazine within and spaced from the inner drum and projecting above the latter, an annular horizontal perforated tube closing the space between the lower ends of the inner drum and the magazine, means to conduct air from the exterior of the outer drum to said perforated tube, an annular hollow band on the outside of the fire pot, said fire pot having a series of openings communicating with said band, means to control the flow of air to said perforated tube and said band, a casing surrounding the drums and forming a space above the latter to which heated air may pass from the space between the inner drum and the magazine, pipes for conducting the heated air from the space above the drums, and means to conduct air from the exterior of the outer drum to the lower part of the space between the inner drum and the magazine, an ash pit under the fire pot, and vertical tubes connecting the upper part of the magazine with said ash pit.

4. In a hot air furnace, a fire pot, an outer drum on the fire pot, an inner drum within and spaced from the outer drum, a vertical magazine within and spaced from the inner drum and projecting above the latter, an annular horizontal perforated tube closing the space between the lower ends of the inner drum and the magazine, means to conduct air from the exterior of the outer drum to said perforated tube, an annular hollow band on the outside of the fire pot, said fire pot having a series of openings communicating with said band, means to control the flow of air to said perforated tube and said band, a casing surrounding the drums and forming a space above the latter to which heated air may pass from the space between the inner drum and the magazine, pipes for conducting the heated air from the space above the drums, and means to conduct air from the exterior of the outer drum to the lower part of the space between the inner drum and the magazine, and damper controlled means for admitting air from the exterior of the outer drum to the interior of the magazine below the tops of the drums and above the annular perforated tube.

In testimony whereof I affix my signature.

FRANK H. CARSON.
